UNITED STATES PATENT OFFICE.

WILLIAM ROACH, OF ARGYLE, TEXAS.

BLOWER FOR FORGES.

SPECIFICATION forming part of Letters Patent No. 710,614, dated October 7, 1902.

Application filed June 19, 1902. Serial No. 112,326. (No model.)

To all whom it may concern:

Be it known that I, WILLIAM ROACH, a citizen of the United States, residing at Argyle, in the county of Denton, State of Texas, have 5 invented certain new and useful Improvements in Blowers for Forges; and I do hereby declare the following to be a full, clear, and exact description of the invention, such as will enable others skilled in the art to which it applies 10 to make and use the same.

This invention relates to blacksmiths' forges; and it has for its object to provide a construction in which a portion of the heat of the fire will be used for generating steam by 15 means of which the blower of the forge will be operated.

A further object of the invention is to provide a construction in which a portion of the heat from the fire-pot will be utilized and in 20 which the waste heat in its passage to the chimney or hood will be absorbed in part, so that the operation of the blower will be economical.

In the drawings forming a portion of this 25 specification, and in which like numerals of reference indicate similar parts in the several views, Figure 1 is a vertical section through a forge and showing in elevation the blower and the engine for operating it. Fig. 30 2 is a detail view of the fire-pot. Fig. 3 is a front elevation of the fire-pot and boiler, with their connecting-pipes. Fig. 4 is a vertical section showing the cast fire-pot.

Referring now to the drawings, there is 35 shown a forge comprising a base 5, built of bricks or other material, and at the rear end of which is the hood 7, through which the products of combustion pass to the chimney. In a depression in the upper face of the base 5 40 and beneath the hood 7 is arranged the fire-pot 6, the wall of which is in the form of an inverted bee-hive coil, at the lower minor end of which is an opening with which is connected the air-feed pipe 8, which leads from 45 a blower 9, which when operated forces the air up through the bottom of the fire-pot and induces combustion of the fuel in the fire-pot in the usual manner.

Arranged between the fire-pot and hood and 50 slightly in the rear of the fire-pot is the water-back 10, having perforations in its front side, in which are screwed the short sections of

pipe 11, which are closed at their free ends, these pipes extending part way over the fire-pot, so as to intercept the major portion of 55 the heated products of combustion in their passage from the fire-pot to the hood, these hot gases striking the water-back 10 and acting to heat it.

Connected with the opposite ends of the 60 coil forming the fire-pot are the pipes 13 and 14, which are connected at their upper ends to the bottom of the water-back 10 at opposite sides of the latter, so that a circulation 65 of water from the fire-pot to the water-back is secured and an efficient heating of the water results.

On the back of the support 15 for the hood is a shelf 16, on which is mounted the engine 17, connected by the feed-pipe 18 with the top 70 of the water-back 10, the engine being provided also with an exhaust-pipe 19, which discharges upwardly into the hood. The blower 9 is supported on the shelf 20 at the back of the base 5, and a belt 21 connects the blower 75 with the engine.

The blower is provided with a handle 22 of usual arrangement for operating it initially while the water in the boiler is being heated to a degree sufficient to produce steam enough 80 to operate the engine, after which the engine operates the blower.

In Fig. 4 of the drawings there is shown a construction of fire-pot in the form of a casting. The walls of this casting are hollow, the 85 sides of the walls lying close together, so that the water in the walls will be quickly heated and proper circulation of the water from the fire-pot to the water-back of the boiler will be insured. The cast fire-pot has nipples 23 90 and 24 for attachment of the pipes 13 and 14 to connect the fire-pot with the water-back.

It will be understood that in practice other modifications of the construction shown may be made and that any suitable materials and 95 proportions may be used for the various parts without departing from the spirit of the invention.

What is claimed is—

1. A forge comprising a base having a hood 100 supported thereabove, a fire-pot mounted in the base and having a hollow wall and an opening through its bottom, a blower having an air-pipe connected with the opening in the

bottom of the fire-pot, a boiler comprising a water-back having laterally-extending tubes projecting part way over the fire-pot and between it and the hood, water-pipes connecting the water-back with the fire-pot, a steam-engine operatively connected with the blower and a steam-feed pipe leading from the water-back to the steam-engine.

2. A forge comprising a base having a hood mounted thereon, a fire-pot mounted in the base and consisting of a downwardly-tapered pipe-coil, a water-back disposed between the fire-pot and hood, pipes connecting the bottom of the water-back with the ends of the coil of

the fire-pot, said water-back having pipes engaged in its face and extending part way over the fire-pot between it and the hood, a steam-engine, a steam-feed pipe leading from the water-back to the steam-engine, a blower operatively connected to the engine and an air-feed pipe leading from the blower to the lower end of the coil of the fire-pot.

In testimony whereof I affix my signature in presence of two witnesses.

WILLIAM ROACH.
